UNITED STATES PATENT OFFICE.

JAMES L. GILL, OF BRIDGETON, NEW JERSEY.

WINDOW-SCREEN.

1,133,127.

Specification of Letters Patent. Patented Mar. 23, 1915.

Application filed March 20, 1914. Serial No. 826,063.

To all whom it may concern:

Be it known that I, JAMES L. GILL, a citizen of the United States of America, residing at Bridgeton, in the county of Cumberland and State of New Jersey, have invented new and useful Improvements in Window-Screens, of which the following is a specification.

This invention relates to window screens, and particularly to that class in which a portion of the frame thereof is adjustable and adapted to contract and expand, to conform to varying widths of window frames, as well as to readily, and removably secure the screen in place within the grooves in which the window sashes slide.

Another object is to provide a resilient means for removably securing either or both of the adjustable portions of the screen frame in contracted position.

Further advantages of the invention are fully brought out in the following specification, when read in conjunction with the accompanying drawing, in which:—

Figure 1 is a front elevation of the device in its preferred form; Fig. 2 is a sectional view on the line 2—2 of the Fig. 1; and Fig. 3 is a sectional view on the line 3—3 of Fig. 1.

Referring to the drawings, a window screen frame is shown as comprising upper and lower sections 1 and 2, end sections 3 and a woven wire gauze 4. The sections 3 are narrowed, as shown in Fig. 3, and co-operate with separate, relatively movable sections 5, having an extension 6, adapted to slide upon the adjacent sections 3 as the positions of the former are shifted with respect thereto, to prevent flies or other insects from passing therebetween.

Between the adjacent sections 3 and 5 and tending to press the same apart are resilient members 7, preferably secured to the former and frictionally engaging the latter. On the other hand, to prevent a total separation of said sections, pins 8, having angularly bent portions 9, are secured to the adjustable sections 5 and pass inwardly through apertures 10 in the sections 3, said bent portions being slidable in recesses 11 and normally inclosed by a plate 12.

Substantially midway of the length of the sections 3 are apertures 15, through which resilient pins 16, having reversely bent end

portions 17 and secured at one end in the sections 5, are adapted to readily pass. 55 When the last-named sections are in extended position, the bent portions 17 of the pins 16 lie within the apertures 15, but when the said sections are forced inwardly, the resiliency of said pins, after they are moved 60 longitudinally inward, causes said portions 17 to snap upwardly into the position shown in Fig. 1, wherein they co-operate with the inner surface of the sections 3 to temporarily maintain the sections 5 in contracted position. 65 From this position said last-named sections will snap outwardly into engagement with the window frame 20, upon pressing downwardly upon the bent portions 17, thus permitting the springs 7 to force the 70 pins outwardly through the apertures 15.

In devices of this character, after moving the adjustable sections inwardly before placing the screen in the window frame, there is no means for temporarily retaining 75 them in such position and from which they can be readily released. This device particularly provides such a device, which, however, may be altered in its details of construction and operation, and yet fall within 80 the spirit of the present invention as well as within the scope of the appended claim.

I claim:

A window screen comprising a frame, the end rails of which are narrower than the top 85 and bottom rails thereof, a wire mesh fabric supported by the frame, the said end rails being formed with slots, leaf springs fixed in spaced relation to each other at the outer edges of the end rails of the frame, extensible sections having cut-away portions for receiving the end rails of the frame whereby the spring will act upon the said sections for spacing the same from the frame, and resilient pins mounted in the sections and 90 passed through the slots in the said end rails and having eye heads for snapping engagement with the end rails for sustaining the sections in retracted position relative to the frame. 100

In testimony whereof I affix my signature in presence of two witnesses.

JAMES L. GILL.
